UNITED STATES PATENT OFFICE.

HULBERT A. YERKES, OF FOREST HILLS, NEW YORK, ASSIGNOR TO COLUMBIA GRAPHOPHONE MANUFACTURING COMPANY, OF BRIDGEPORT, CONNECTICUT, A CORPORATION OF DELAWARE.

DESIGN FOR A PHONOGRAPH CABINET.

Application filed April 23, 1923. Serial No. 5,901. Term of patent 3½ years.

To all whom it may concern:

Be it known that I, HULBERT A. YERKES, a citizen of the United States, residing at Forest Hills, in the county of Queens and State of New York, have invented a new, original, and ornamental Design for Phonograph Cabinets (Case No. 4), of which the following is a specification, reference being had to the accompanying drawing, forming part thereof.

The figure is a perspective view of a phonograph cabinet, embodying the new design.

I claim:

The ornamental design for a phonograph cabinet, as shown.

HULBERT A. YERKES.
